CRANKSHAFT ALIGNMENT MACHINES

William Homer Brown, Amarillo, Tex.

Application October 7, 1952, Serial No. 313,539

2 Claims. (Cl. 153—52)

This invention relates to means for detecting disalignment in and straightening shafts, and more particularly for straightening crankshafts of the kind including end main bearing journals, offset journals and intermediate main bearing journals.

Shafts of this character for different makes and models of engines, by way of example, vary in length as to the distance between end main bearing journals and also the zone of greatest disalignment, either when the shaft is new or used, may not always occur at the central zone between the end main bearing journals so that, in order to straighten the shaft into axially aligned condition as to the main bearing journals, it may be necessary to stress the shaft by a pressure applying device at one of the intermediate main bearing journals nearer to one of the end main bearing journals than the other, or it may be necessary to stress the shaft successively at two or more of the intermediate main bearing journals.

It has been proposed in the past to provide shaft straightening machines which are adapted to receive shafts of different lengths and associate with same pressure applying devices, such as a hydraulic ram, jack-like unit, a prying instrument or lever, etc., but these machines have some objectionable features in that they are either rather complicated in construction and take considerable room in shops, or each has a single pressure applying device located in a fixed zone with respect to the machine frame and hence it is necessary to move the shaft or work supports with respect to the pressure applying device, so that the shaft may be stressed at the zone of greatest disalignment.

The principal objects of the present invention are to provide a machine for the purpose set forth which is low in cost of manufacture and compact, such as by mainly using rolled metal sections of great strength, as I beams and channels, in construction of the machine frame; and to provide work supports that are adjustable with respect to the frame so as to accommodate shafts of different lengths, a suitable bed for an alignment indicating means bodily movable thereupon whereby test for disalignment may be made along the shaft to determine the zone of greatest disalignment, and a bodily movable pressure applying device carried by the frame, so that it may be moved along the frame to a position where it may be used to stress the shaft at that zone of greatest disalignment, without the necessity of moving the shaft longitudinally to a position in operative relation to the pressure applying device for such purpose.

Another object is to provide a machine which may use any of the many suitable hydraulic ram units, pump units manually operable by a hand lever, and flexible connecting hose available on the open market for the purpose of stressing the shaft to straighten same, and so that the pump unit may be located at either end of the machine to be conveniently operated by either a left-handed or right-handed workman. Examples of such ram and pump units and hose are shown in Pfauser 2,165,504 dated July 11, 1939.

2

Other objects will appear in the following detailed description of a highly satisfactory embodiment of my invention, taken in connection with the accompanying drawings, forming a part of this specification, and in which drawings:

Fig. 1 is a front elevational view of a machine made according to this invention and showing a crankshaft in position for testing and for stressing if disaligned with respect to the main bearing journals.

Fig. 2 is an end elevational view of the same.

Fig. 3 is an enlarged vertical sectional view, on the line 3—3 of Fig. 1.

Fig. 4 is an enlarged view partly in elevation and partly in vertical section of a suitable work support, substantially on the line 4—4 of Fig. 1.

Fig. 5 is a view partly in plan and partly in horizontal section of a suitable alignment indicating means for use in testing the shaft for disalignment.

Fig. 6 is a view on an enlarged scale of the alignment indicating means, partly in rear elevation and partly in vertical section.

In the example shown, the machine comprises a frame 7 including an upper horizontal beam 8, serving as an upper elongated reaction member, and a lower horizontal beam 9, serving as an elongated base or lower reaction member; work supports 10 adjustable along the beam 9 and each including an upright block 11 provided with a bearing 12 for receiving the end main bearing journal 14 of a crankshaft 15; an alignment indicating means 16 including an element 17 such as a rod for peripherally engaging any one of a plurality of intermediate main bearing journals 18 of the shaft 15, and preferably a relatively heavy base 19 machine surfaced at its bottom, freely slidable upon a planar surface 20 of the beam 9; a carriage 21 slidable along the beam 8; and a pressure applying device 22 supported by and depending from the carriage 21 and including a vertically movable element 24, equipped with a contacting appliance 25 for engagement upon any one of the journals 18 of shaft 15.

In the example shown, the pressure applying device 22 is a ram including an hydraulic cylinder 27 and the element 24 is a plunger, the upper end portion of which operates in the cylinder and is retracted by a spring, not shown in the drawing, in the well known manner when pressure is relieved in the bore of the cylinder. Associated with the device 22, in the example shown, is a pump unit 28, mounted upon a shelf 29 carried by frame 7 adjacent to the right end of beam 9, and including a cylinder 30, a hand operated lever 31 and a relief valve 32; a flexible hose 33 operatively connecting the cylinders 27 and 30; and a pressure gage 34 conveniently disposed adjacent to cylinder 27 for indicating pressure in the latter. Suitable characteristics of most of these elements will be found in the aforesaid Patent 2,165,504.

The frame 7 preferably includes beams 8 and 9 of I-section disposed with the webs 35 in the same common vertical plane. The under face 36 of the lower flange 37 of beam 9 is machine surfaced to provide a smooth face for a portion of the carriage 21 to engage, and the upper flange 38 of beam 9 is also machine surfaced to provide the planar surface 20 for surface contact with base 19 of the alignment indicating means 16 and the portions of the work supports 10 as hereinafter described. The lower flange 39 of beam 9 need not be machine surfaced. The frame 7 also includes standards 40 of channel cross-section to which the ends of beams 8 and 9 are welded, as by welds 41 to the web 42 and by welds 43 to the flanges 44 of the standards. The standards are mounted upon the mid-portions of rails 46 and secured thereto by welds 47. Thus a very sturdy frame is pro-

vided which may be placed broadside, close to a wall. The work supports 10 each includes a horizontal base plate 48 to which the block 11 is symmetrically secured by weld 50, the plate having its underside 51 machine surfaced for engagement upon the machined or planar surface 20 of beam 9 and is made sufficiently long in a direction transversely of the beam to provide projecting portions 52 to the undersides of which are secured the tops of front and rear vertical plates 53 as by welds 54. These plates extend slightly below the plane of the bottom of flange 39 of beam 9 and a cross bar 55, carrying a set screw 56, is detachably secured to the under portions of plates 53 as by bolts 57. By this arrangement, the work supports 10 may be assembled on or removed from the beam 9 and adjusted longitudinally of the beam to position them according to the spacing of the end main bearing journals of the shaft and retained in place by the set screw 56 turned tight against the under surface of the beam. The bearing 12 of each block 11 may be of any suitable type, but in the example shown is in the nature of a recess, the bottom walls 58 of which converge downwardly to an apex 59, thus adapting the blocks to receive journals of various diameters.

The alignment indicating means 16 in the example shown includes, in addition to the rod 17 and base 19, spaced standards 61, mounted upon one end portion of the base 19, between the upper portions of which the central portion of a pivot bar 62 is disposed and adjustably secured in place by a clamp bolt 63 equipped with a wing nut 64, the shank of the bolt extending through aligned apertures 65 and 66 in the upper ends of the standards 61 and the central portion of the bar 62. By means of upstanding guides 67, at the ends of the bar 62, the rod 17 is longitudinally slidable through apertures 68 in the upper portions of the guides. One end 69 of the rod is for engagement with the selected main bearing journal of the shaft to be tested and operated on and the other end 70 is in operative relation to a gage 71 calibrated in any suitable manner, such as for measurements to the thousandths of an inch each side of a zero graduation 72 with which an indicator hand 73 is associated. By this arrangement the alignment indicating means may be moved by sliding the same upon the planar surface 20 to an approximate position for testing the shaft at the selected zone, and if necessary the parts adjusted so that the rod 17 has its axis normal to the axis of the journal in the selected zone, as by manipulation of the clamp bolt 63, nut 64 and pivot bar 62 (according to the diameter of the particular journal of the shaft while resting upon the work supports 10). By rotating the shaft 15 while the end 69 of rod 17 engages the journal in the zone of the shaft undergoing test, the alignment indicating means may be manipulated to determine the extent, if any, to which the shaft is disaligned marking the zone of greatest disalignment, and the value of the graduation at which the hand 73 stops in its movement away from the zero graduation. This test may be repeated at each intermediate main bearing journal to determine the zone of the shaft which has the greatest disalignment and so marked is the zone of application of force by use of the pressure applying device 22 to stress or straighten the shaft into an aligned condition, in the well known manner.

The carriage 21 is preferably made of a horizontal plate 75, the upper face of which is machine surfaced for engagement with the underface 36 of flange 37, and attaching members 76 of angular cross-section, one at the front edge and one at the rear edge of the plate, the one flange 77 of each being attached in any suitable manner to its respective edge of the plate, and the other flange 78 of the member 76, riding freely upon the upper surface 79 of the beam flange 37.

The plate 75 is provided with a centrally disposed screw threaded aperture 80 for the reception of a stud bolt 81 which is also in screw threaded engagement with

the cylinder 27 of ram unit at a recess 82 in the upper end of the cylinder. This recess is found in ram cylinders in common use as is shown in the aforesaid Patent 2,165,504.

5 The contacting appliance 25 may be of any suitable or approved type and in the example shown is provided with a downwardly opening recess 83 the walls 84 of which converge upwardly to an apex 85 whereby the journal acted upon by the pressure applying device will 10 have line contact with the walls 84, regardless of the diameter of the journal. In practice I have found that, by machining the walls 84 of recess 83 each at an angle of 70° to the vertical, the two line contacts between appliance 25 and the journal of the shaft acted upon distributes the force so that the chance of leaving a dent in the journal is greatly reduced, also stability is provided to overcome any tendency of the ram jumping off the shaft at high pressure.

It may be noted that, in the example shown and especially upon consideration of Figs. 2 and 3, the machine 20 is very compact and sturdy since the webs 35 of the upper and lower reaction members 8 and 9 are in the same vertical plane in which is also located the axes of the pressure applying member 24 and bearings 12 of the work supporting blocks 10.

The approved procedure in using the machine is to first position the shaft to be tested with the end main journals in the bearings 12 of blocks 10. In practice it has been found that the block 10 nearest the pump unit 28 seldom needs to be moved if initially placed about 6" from the adjacent standard 40; the other block 10 being adjusted along the beam 9 and fixed as by turning set screw 56 tight against beam 9, according to the distance between the journals 14 of the shaft. It is good practice to lubricate these journals 14 and bearings 12 to allow easy rolling of the shaft. The intermediate journals 18 are then acted upon by the alignment indicating means 17, in succession, to determine the zone of greatest disalignment, if any, in the shaft. The means 16 is movable upon the planar surface 20, but due to its weight need not be held by hand in a selected position while making tests. The means 16 is rendered adjustable, as by loosening the nut 64 and changing the position of bar 62, and parts carried thereby, until the axis of rod 17 points directly toward the center line of the shaft when the end 69 of the rod contacts the periphery of the journal being tested, after which the nut 64 should be turned tight. Adjustment of the means 16 may be necessary only when changing to a testing operation of a shaft having journals 18 of greater or less diameter than those of a shaft previously tested and for which the means 16 was properly adjusted.

With the means 16 properly adjusted and with the end 69 of rod 17 contacting the journal 18 to be tested, the operator rotates the shaft 15, by hand to determine any run-out by observing the hand 73, noting the extent of run-out (if the hand does not point at all times to zero) and mark, as by use of chalk, the spot of greatest disalignment. This testing procedure is then followed in connection with each journal 18 of the shaft, to determine which particular one shows disalignment to the greatest extent. When this is determined, the carriage 21 is moved along beam 8, to a position where the appliance 25 is centered directly over the chalk mark of the journal 18 last referred to, and when said chalk mark is uppermost. It will be noted that the preferred formation of the recess 83 has no tendency to remove the chalk mark referred to. Also, it is important to note that the journal 18 having the greatest run-out may be one adjacent to, or it may be one quite remote from either end journal 14, and it is not necessary to move the shaft 15 and blocks 10 to a position with respect to the pressure applying device 22 for operation upon that particular journal 18.

In the example shown, the device 22 is operated by 75 hand manipulation of the lever 31, the operator observing

the gage 34 so as to build up the pressure which experience has taught him appropriate for a first stressing of the shaft. In practice I have found approximately 1000 lbs. is suitable. This is followed in succession by manipulation of the relief valve 32, testing with the means 16 while rotating the shaft 15, and subsequent stressing of the shaft at the opposite side from that to which pressure was previously applied and testing until the hand 73 does not deviate from the zero graduation upon rotation of the shaft. This is done to break down molecular stresses which caused the shaft to be disaligned, either through some such cause as defective cooling methods when manufactured, through use or accident. There are occasions where the shaft to be acted upon has a double bend, that is, one journal 18 running out in one direction and another journal 18 in another direction. This requires acting upon each of such journals by the means 16 and device 22 until the former shows no disalignment at any of the bearings 18. However, the support of the device 22, by carriage 21 on the upper reaction member 8 also greatly facilitates this operation.

It will be noted that the machine is very symmetrical. If it is desired that the pump unit 28 be located on the left end of the machine for convenient operation by a left-handed person to manipulate the lever 31, the machine may be turned end for end, the hose 33 brought in back of the machine and the pump unit 28 changed end to end and again secured to the shelf 29.

I claim:

1. A machine for straightening a crankshaft of the type including end main bearing journals and intermediate main bearing journals, comprising a frame including parallel upper and lower spaced apart, horizontal I-beams disposed with their webs in the same common vertical plane, spaced apart work supports carried by and movable longitudinally of said lower beam, each of said supports comprising a horizontal plate at least coextensive

5
10
15

with the width and slidably engaging the upper face of the upper flange of said lower beam, retaining means carried by said plate releasably engaging said lower beam for retaining it in adjustable fixed relation with said lower beam, and a bearing disposed above and carried by said plate, said bearings of said work supports disposed with their axes aligned in the said common plane, for receiving the end bearing journals of the crankshaft, a carriage comprising a horizontally disposed plate coextensive with the width and slidably engaging the under face of the lower flange of said upper beam, and attaching members at opposite sides of said plate including flanges engaging upon and slideable along the lower flange of said upper beam, a pressure applying device, including a vertically movable plunger, secured to said plate and extending downwardly from the underside thereof with the axis of the plunger in the plane common to the webs of said beams, and a contacting appliance on the lower end of said plunger for engagement upon a selected intermediate 20 main bearing journal of the crankshaft to be straightened.

2. The machine for straightening a crankshaft as specified in claim 1 in which the said retaining means of each work support comprises vertical plates at each side of said lower beam depending from the ends of its said horizontal plate, a cross bar connected to the lower portions of said vertical plates, and a set screw carried by said cross bar, the axis of said set screw being in said common plane.
